United States Patent Office

Des. 178,483
Patented Aug. 14, 1956

178,483

KEY RING

John H. Bacon, Wellesley, Mass.

Application February 9, 1956, Serial No. 40,094

Term of patent 14 years

(Cl. D17—14)

FIG. 1

FIG. 2

Figure 1 is a front elevation of a key ring showing my new design; and,

Figure 2 is a side elevational view thereof.

I claim:

The ornamental design for a key ring, as shown.
